[57] CLAIM

The ornamental design for a lavatory, as shown and described.

DESCRIPTION

FIG. 1 is a perspective view taken from the top, front and right of a lavatory showing our new design;

FIG. 2 is a top plan view thereof;

FIG. 3 is a cross-sectional view thereof taken on line 3—3 of FIG. 2;

FIG. 4 is a cross-sectional view thereof taken on line 4—4 of FIG. 2;

FIG. 5 is a partial cross-sectional view thereof taken on line 5—5 of FIG. 2; and,

FIG. 6 is a top plan view of a second embodiment thereof.

The fragmentary broken line representations of a countertop in FIG. 1 and fitting mounting holes in FIGS. 1, 2 and 6 are for the purpose of illustration only and form no part of the claimed design.

FIG. 1

FIG. 2

FIG. 3

FIG. 4

FIG. 5

FIG. 6
